[57] **CLAIM**

The ornamental design for a decorative top edge cover for pickup truck side walls, as shown and described.

DESCRIPTION

FIG. 1 is a perspective view of the decorative top edge cover for pickup truck side walls of the present invention; FIG. 2 is a top plan view thereof, shown at a reduced scale for ease of disclosure;

FIG. 3 is a bottom plan view thereof, shown at a reduced scale for ease of disclosure;

FIG. 4 is a rear elevational view thereof, shown at an enlarged scale and broken away in the middle for clarity of illustration;

FIG. 5 is a front elevational view thereof, shown at an enlarged scale and broken away in the middle for clarity of illustration;

FIG. 6 is an end elevational view thereof as viewed from the right of FIG. 1, shown at an enlarged scale for clarity of illustration;

FIG. 7 is an end elevational view as viewed from the left of FIG. 1, shown at an enlarged scale for clarity of illustration; FIG. 8 is a perspective view of a second embodiment of the design for a decorative top flange cover for pickup truck side walls;

FIG. 9 is a top plan view thereof, shown at a reduced scale for ease of disclosure;

FIG. 10 is a bottom plan view thereof, shown at a reduced scale for ease of disclosure;

FIG. 11 is a rear elevational view thereof, shown at an enlarged scale and broken away in the middle for clarity of illustration;

FIG. 12 is a front elevational view thereof, shown at an enlarged scale broken away in the middle for clarity of illustration;

FIG. 13 is an end elevational view as viewed from the right end thereof, shown at an enlarged scale for clarity of illustration;

FIG. 14 is an end elevational view as viewed from the left end thereof, shown at an enlarged scale for clarity of illustration;

FIG. 15 is a perspective view of a third embodiment of the design for the decorative top edge cover for pickup truck side walls;

FIG. 16 is a top plan view thereof, shown at a reduced scale for ease of disclosure;

FIG. 17 is a bottom plan view thereof, shown at a reduced scale for ease of disclosure;

FIG. 18 is a rear elevational view thereof, shown at an enlarged scale and broken away in the middle for clarity of illustration;

FIG. 19 is a front elevational view thereof, shown at an enlarged scale and broken away in the middle for clarity of illustration;

FIG. 20 is an end elevational view thereof as viewed from the right end of FIG. 15, shown at an enlarged scale for clarity of illustration; and,

FIG. 21 is an end elevational view as viewed from the left end of FIG. 15, shown at an enlarged scale for clarity of illustration.
